UNITED STATES PATENT OFFICE.

CARLOS B. MIRICK, OF WASHINGTON, DISTRICT OF COLUMBIA.

ELECTRICAL DISTANT-CONTROL SYSTEM.

Application filed September 1, 1923. Serial No. 660,596.

My invention relates broadly to distant control systems, and more particularly to a control circuit for a radio transmitter, and a selectively responsive circuit for a radio receiving apparatus whereby particular controls may be caused to function individually or simultaneously.

One of the objects of my invention is to provide a selective control system for radio transmitting apparatus and a selective receiving circuit arrangement whereby particular relay circuits may be operated in accordance with the operation of particular circuits at the radio transmitter.

Another object of my invention is to provide means at a transmitter for controlling particular oscillator circuits independently or a plurality of oscillator circuits simultaneously whereby they cause corresponding circuits at a receiving station to be selectively closed to control particular circuits independently or groups of circuits simultaneously.

Another object of my invention is to provide a control apparatus which may be connected to a radio transmitter to modulate the output of the transmitter at a selected frequency of a range of frequencies, or to modulate the transmitter with a complex wave resulting from a combination of more than one frequency, and means at the receiving station for selectively closing particular circuits or a plurality of circuits upon the receipt of modulated energy from the transmitting station.

Other and further objects of my invention will be understood from the following specification by reference to the accompanying drawings, in which:—

Figure 1 represents diagrammatically the arrangement of the control apparatus at the radio transmitting station; Fig. 2 is a diagrammatic representation of the control apparatus at the radio receiving station; and Figs. 3 and 4 are theoretical diagrams explaining the principle of operation of the control circuits of my invention.

In applying the circuits of my invention to a radio transmitter, the usual radiating

system 1 connected to a source of carrier wave frequency 2 is provided with and modulated by my control apparatus represented at 4. The modulator includes a plurality of microphone oscillators or vibrators 5, 6, 7 and 8 energized by battery 9 and adjusted independently to different frequencies. The output of these vibrators is connected through switching device 10 to the four intermediate transformers 15, 16, 17, and 18. The four oscillators and transformer circuits have been selected merely for purposes of illustration and it will be understood that more or less may be used. If lever 20 is brought in contact with terminal 5^a of switch 10, a circuit is closed which permits the output current of oscillator 5 to pass through the primary 15^a of transformer 15. The same holds true for any of the other of the oscillators 6, 7, and 8; that is, oscillator 6 may excite the primary of transformer 16 by movement of lever 20 into connection with contact 6^a, or oscillator 7 may be connected with transformer 17 by movement of lever 20 into contact with 7^a, or transformer 18 may be energized by oscillator 8 by contacting lever 20 with contact 8^a. The secondaries 15^b, 16^b, 17^b, and 18^b of the intermediate transformers 15, 16, 17, and 18 are connected in series and supply energy to the primary winding 21 of transformer 22 whose secondary 23 is connected to modulate the output of the continuous wave radio transmitter 2. The lever 20 can make contact with two sectors at once and thus connect simultaneously any oscillator with the adjacent one either side of it, but not with the fourth oscillator. That is, 5 can be connected with 6 and 8 but not with 7; 6 can be connected with 5 and 7 but not with 8, and so on by movement of lever 20 in different positions.

My control system is particularly applicable in maneuvering aircraft without a pilot. I construct the switch 10 in the form of a "joy stick" identical with the "joy stick" provided in aircraft for controlling the machine. An operator at the radio transmitter at a shore station who is an expe-

rienced aviator may therefore move the lever 20 in the same manner in which he is accustomed to operating the "joy stick" in aircraft and control circuits at a radio receiver, on board an aircraft as will be hereinafter described, which in turn control the operation of the particular functions necessary in the flight of the aircraft such as operating the elevating planes, the rudder, 10 banking the machine or controlling the engine. My control apparatus is not limited to operation with aircraft but is applicable to any circuits or objects which are to be controlled at a distance.

15 The modulated output of the transmitter is radiated from the antenna system 1, and at the receiving end of the system the signal therefrom is collected by antenna system 24 amplified and rectified by receiver 25 and 20 finally supplied to the input of a relay apparatus represented at 26. The relay 26 includes a master tube 27 and a plurality of tubes 28, 29, 30 and 31 corresponding to the 25 number of control circuits at the transmitter. The tuned resonant relays 32, 33, 34, and 35, are constructed to respond each to a pitch of modulation of the corresponding oscillators 5, 6, 7, and 8 of the transmitter and are series connected in the plate circuit 30 of the master tube 27 supplied by B battery 46. Suitable resonant relays have been described by me in a copending application Serial No. 660,597, filed September 1, 1923. If modulator 5 is connected to control transmitter 1, relay 32 at the receiving station responds or correspondingly other controls may function to operate particular relays, or if a combination of controls is operated simultaneously at the transmitter a combination of relays may be closed at the receiver. If, for example, oscillators 5 and 6 are connected simultaneously, as explained, by placing switch lever 20 on both 5^a and 6^a contacts, relays 32 and 33 will function 45 simultaneously with their respective controlled circuits and similarly various combinations may be secured. Each of the resonant relays 32, 33, 34, and 35 independently control the input circuit of electron tubes 28, 29, 30 and 31 respectively, the output circuit of each tube containing secondary relays 36, 37, 38 and 39, an arrangement 50 fully disclosed in a copending application Serial No. 660,598, filed September 1, 1923. 55 The filament electrodes of the electron tubes are energized from battery 40. A constant negative potential is maintained on the grid electrodes of the tubes 28, 29, 30, and 31 from battery 41 connected across the input circuit 60 of each of the tubes through resistances 42, 43, 44, and 45. The independent resonant relays 32, 33, 34, and 35 are provided with pairs of contacts 47, 48, 49 and 50 which are normally open, but when any particular relay or group of relays become energized

these contacts are closed and charge the grids of the respective tubes with positive polarity derived from battery 51, causing a plate current to flow in the particular tube and the secondary relay in that plate circuit to be 70 actuated. Normally when the contacts 47, 48, 49 or 50 are open the grids are charged negatively and accordingly there will be zero 75 plate current in the particular tube circuit so that a maximum value of plate current will be obtained upon the closing of the contacts.

The secondary relays are provided with contacts 52, 53, 54, and 55 with connections which lead off to the circuits to be controlled. 80

While I have indicated separate batteries for supplying the negative grid bias and the positive charging potential, separate plate batteries for the master tube 27 and separate plate batteries for the relay tubes 28, 29, 30, and 31, it will be understood that this is represented for the sake of clearness and that common sources of potential may be employed. In securing this simultaneous action of relays, two things are essential. One is, that the wave form of the resultant E. M. F. derived from two oscillators working at the same time must approach that of a wave in which instantaneous values of E. M. F. due to each one singly are added algebraically. Such a resultant is obtained by placing the secondaries of the transformers 15, 16, 17 and 18 in series as shown in Fig. 1. Were the secondaries 100 of these transformers connected in parallel, the resultant wave would not be so formed and the operation of the tuned relays in separating again the wave into its two components would not be as effective. This 105 difference has been represented graphically in Figs. 3 and 4, wherein curve 56 represents the correct combination of two waves at different frequencies as in the case of 110 transformers connected in series as represented in Fig. 1, and Fig. 4 shows the incorrect combination of two waves of different frequencies as with transformers connected in parallel. Wave 56 represents the effect of one modulator upon the transmitter and the corresponding received frequency. The 115 curve 58 is the resultant combined wave of the two waves 56 and 57 which would be received upon simultaneous operation of the two oscillators. The desired wave form is 120 shown in Fig. 3.

The second point of importance is, that 125 the waves to be combined should be as nearly as possible of pure sine form without harmonics. This condition is approached by using condensers 59, 60, 61, and 62 to tune the circuits electrically to the periods 130

of the oscillators and resonant relays at the receivers tuned by condensers 63, 64, 65, and 66. Such condensers may be used in parallel or series at various points in the 5 circuit, but I prefer to use them as indicated in the drawings.

The system employs a single wavelength or carrier wave for radio transmission, which carrier wave is modulated at a number 10 of different frequencies, corresponding to the number of functions to be controlled, and these functions can be controlled either singly or in pairs of two operating simultaneously to operate the controls at the receiver.

While I have described my invention in certain specific embodiments, it is to be understood that modifications may be made and that I intend no limitations other than 20 are imposed by the scope of the appended claims.

What I claim and desire to secure by Letters Patent of the United States is as follows:—

25 1. A radio control system comprising in combination a radio transmitter, means for modulating the output of said transmitter at a plurality of different frequencies, means for receiving the transmitted energy, a master electron tube circuit controlled by the received energy, a plurality of electron tubes each connected to said master tube through a relay mechanically tuned to one of said modulating frequencies, and means connected to each of said tubes and actuated thereby for controlling independent circuits.

2. A radio control system comprising in combination a radio transmitter, means for modulating the output of said transmitter at a plurality of different frequencies, means for receiving the transmitted energy, a master electron tube circuit controlled by the received energy, a plurality of electron tubes each connected to said master tube through a relay mechanically and electrically tuned to one of said modulating frequencies and means connected to each of said tubes and controlled thereby for controlling independent circuits.

50 3. A radio control system comprising in combination means for transmitting a carrier frequency, means for modulating said carrier frequency with a plurality of different frequencies independently or in combination, a receiver, an electron tube connected to said receiver, a plurality of relays connected to said electron tube each mechanically tuned to one of said modulating frequencies, electron tubes connected to and controlled by said relays, and circuit-controlling devices actuated by said electron tubes.

4. A radio control system comprising in combination a radio transmitter, means for modulating said transmitter at a plurality

of different frequencies comprising independent modulating current generators, transformers each having their primary windings connected to one of said generators, means for exciting one or a combination of said transformers, a circuit connecting the secondary windings of said transformers in series and to said radio transmitter, and means for receiving the transmitted energy and controlling separate 70 circuits thereby including relays mechanically tuned to said modulating frequencies controlling electron tube circuits.

5. A radio control apparatus, comprising in combination a radio transmitter and receiver, means for modulating said transmitter at a plurality of different frequencies or combinations thereof, comprising a plurality of generators of different frequencies, a series circuit arrangement for impressing said different frequencies on said modulating means, a switch having a contact for each of said generators, a switch lever arranged to make connection with any one or a pair of said contacts whereby the output 80 of said generators may be impressed on said modulator either singly or in combination with another generator, and receiving means having a plurality of selector circuits arranged to respond individually or in pairs 85 to said transmitted energy.

6. A radio control apparatus, comprising in combination a radio transmitter and receiver, means for modulating said transmitter at a plurality of different frequencies or combinations thereof, comprising a plurality of generators of different frequencies, a series circuit arrangement for impressing said different frequencies on said modulating means, a switch having a contact for each of said generators, a switch lever arranged to make connection with any one or a pair of said contacts whereby the output 90 of said generators may be impressed on said modulator either singly or in combination with another generator, and receiving means having a plurality of relays connected in series, an electron tube having grid, filament and plate electrodes connected to each of said relays, means for normally 95 maintaining all of said grid electrodes at negative potential, means for charging said grid electrodes with positive potential upon closing of said relays and a secondary relay connected to each of said plate electrodes 100 and arranged to be closed either individually or in pairs when said grid electrodes are charged positively.

7. In a radio control system, the combination of a transmitter of a radio carrier frequency modulated at different frequencies, and a receiver including relays mechanically responsive to said modulating frequencies, electron tubes having their grid 105 circuits controlled by said relays, and circuit 110

controlling relays in the plate circuits of said tubes.

8. In a radio control system the combination of a transmitter of a radio carrier frequency modulated at a plurality of different frequencies, and a receiver including relays mechanically selectively responsive to

said modulating frequencies, an electron tube for each of said relays, sources of exciting potential in the grid circuits of said tubes adapted to be controlled by said relays, and circuit controlling relays in the plate circuits of said tubes. 10
